UNITED STATES PATENT OFFICE.

GEORGE A. SMITH, OF HALIFAX, CANADA.

GALVANIC BATTERY.

SPECIFICATION forming part of Letters Patent No. 443,976, dated December 30, 1890.

Application filed July 14, 1890. Serial No. 358,618. (No model.)

To all whom it may concern:

Be it known that I, GEORGE A. SMITH, of 5 Halifax, in the Province of Nova Scotia and Dominion of Canada, have invented a new and Improved Galvanic Battery, of which the following is a specification, reference being had to the annexed drawings, forming a part thereof, in which—

Figure 1 is a vertical transverse section of 10 my improved battery. Fig. 2 is a side elevation of my improved battery, showing the battery-case in section. Fig. 3 is an exterior view of the battery-case, and Fig. 4 is a perspective view of the elements.

Similar letters of reference indicate corresponding parts in all the views.

The object of my invention is to construct a simple, inexpensive, and powerful battery for the use of physicians, surgeons, and experimentalists for generating a strong current for operating induction-coils, galvano-cautery, running motors, and for other purposes.

My invention consists in a battery formed 25 of a cell for containing the exciting-liquid, one or more elements formed of rods of zinc and rods of carbon, and mechanism for plunging and lifting the elements and holding them at any desired height, all as will be 30 hereinafter more fully described.

The cell A, which contains the exciting-liquid B, is inclosed in a case C, in which are arranged the rods a a', forming guides for the board b, which supports the zinc rods c 35 and the carbon rods d. The carbon and zinc rods are mounted in rows in bars e of conducting material, the several rows being separated from each other by plates f, of insulating material. The bars e and the plates f 40 are held in position by bolts g passing through the said bars and plates and through L-shaped plates h h', clamping the several parts together. The bolts g are insulated from the zinc plate by rubber tubes surrounding the 45 bolts. To the bar e, attached to the zinc rods c, is secured a binding-post i, and to the L-shaped plate h' is secured a binding-post j. The lower ends of the rods a a' are secured to the bottom of the case C, while the upper 50 ends of the said rods are received in brack-

ets k k', projecting inwardly from the sides of the case.

In the case C is journaled a rock-shaft E, to which are attached one or more arms l, said arm being connected with an ear m, secured 55 to the under surface of the board b. When there are two battery elements, one arm l will suffice for raising and lowering said elements; but when there are a large number of elements two or more of the arms l will be required. One of the arms l is prolonged beyond the rock-shaft E and is connected with one end of the spiral spring n, the other end of which extends through a bracket o, attached to the side of the case C. The said 60 spring n nearly or quite counterbalances the weight of the battery elements.

Upon the end of the rock-shaft E which projects through the end of the casing C is mounted a lever F, which extends underneath 70 the curved ratchet-bar G, attached to the end of the casing, and serves to raise or lower the elements by turning the rock-shaft E. When the lever F is to be operated by hand, it is arranged as shown in full lines in Fig. 3; but 75 when it is operated by foot it is extended downwardly and its lower end is curved outwardly, as shown in dotted lines in the same figure.

The battery is connected with the induction-coil or other apparatus by wires inserted in the binding-posts i j, and the elements are plunged more or less in the exciting-fluid B by the movement of the lever F. When the battery is not in use, the elements are removed from the solution by moving the lever F in the opposite direction.

The construction of my improved battery affords a large surface to the action of the liquid, and the rods being separated permit 90 of the free circulation of the solution.

A portion of the front of the battery-case is made removable to admit of taking out the battery-cell.

Having thus described my invention, I 95 claim as new and desire to secure by Letters Patent—

1. A battery element comprising alternating rows of carbon and zinc rods, bars of conducting material connecting the rods of each 100

row, insulating-plates between the upper ends of said bars, and the transverse bolts passing through said plates and bars and insulated from the bar connecting the zinc rods, substantially as set forth.

2. A battery element comprising the alternating rows of carbon and zinc rods, bars of conducting material connecting the rods of each row, insulating-plates between said bars, the L-shaped plates at opposite sides of the element, and the transverse bolts passing through the vertical members of the said plates and through the said bars and insulating-plates, the bolts being insulated from the bars connecting the zinc rods, substantially as set forth.

3. The combination, with the cell having vertical rods or guides, of an element in the

cell provided with a board movable vertically on the said rods, a pivoted arm within the cell and connected to said board, and a lever on the outer side of the cell for operating the said arm, substantially as set forth.

4. The combination, with the cell having vertical rods or guides, of an element in the cell provided with a board movable vertically on said rods or guides, and a counterbalanced pivoted arm within the cell connected to the said board and provided exterior to the cell with an operating-lever, substantially as set forth.

GEORGE A. SMITH.
